GARMENT SPOT-REMOVING DEVICE

David A. Freeman, Chicago, Ill., assignor to Dryco Corporation, Syracuse, N. Y., a corporation of New York

Application April 11, 1950, Serial No. 155,273

2 Claims. (Cl. 299—86)

1

This invention relates to a device used in commercial cleaning establishments for removing spots from soiled garments and the like.

The device, which is referred to in the trade as a spotting gun, is used in combination with a steam supply and a pressurized blending or ring-obliterating fluid supply. Heretofore in removing spots from a garment it was customary to use two separate guns, one for the steam and one for the blending fluid, and also a separate brush, the latter which helped loosen dirt particles when necessary. Thus the use of a brush and separate guns for removing the spots was awkward for the operator to handle as well as time-consuming.

One of the objects of this invention is to provide, therefore, a device which combines the brush and the various guns into one unit.

It is a further object of this invention to provide a device which is lightweight and convenient to handle and combines in one unit the various guns and brush as heretofore required for effectively removing spots from a soiled garment.

It is a further object of this invention to provide a device which enables live steam and blending fluid to be discharged therefrom separately or in concert.

It is a still further object of this invention to provide a spotting gun which is simple in construction, efficient in operation, and inexpensive to produce.

Further and additional objects will appear from the description, accompanying drawings, and appended claims.

In accordance with one embodiment of this invention, a device is provided comprising a steam conducting means connected to a steam supply and a fluid conducting means connected to a pressurized blending fluid supply. A handle is provided which is connected to the steam and fluid conducting means. The outlets for the conducting means are exposed and arranged so that the discharge therefrom is directed to substantially the same area on a garment being cleaned while the device is held in substantially a fixed position with respect to the garment.

For a more complete understanding of the invention reference should now be made to the drawings, wherein:

Figure 1 is a side elevational view of a spotting board showing the device and its associated mechanism. A second pressurized tank for a different type of blending fluid is shown in dotted lines when the modified device shown in Fig. 5 is used.

2

Fig. 2 is a perspective view of one form of the device.

Fig. 3 is a fragmentary side elevational view of the device shown in Fig. 2.

Fig. 4 is an end view of the device shown in Fig. 3.

Fig. 5 is a perspective view of a modified form of device.

Fig. 6 is a fragmentary perspective view of another modified form of device wherein no steam conducting means is provided.

Referring now to the drawing and more particularly to Fig. 1, one form of the device 10, to be hereinafter referred to as a gun, is shown used 15 in combination with a conventional type spotting board or table 11. The table consists of a top 12 over which the garment to be cleaned is laid, a support column 13 in which the steam outlet, not shown, is located, and a stand 14 for said column which is bolted to the floor 15. A plurality of foot pedals 16 are provided on stand 14, one of 20 which controls the output of the steam outlet.

Resting on floor 15 adjacent column 13 is a 25 pressurized tank 17 which contains the blending or ring-obliterating fluid. Mounted on the top of the tank 17 is a pressure gauge 18, and an adapter 20. The adapter enables an outside source of air-pressure, such as the common pneumatic supply of the establishment, to be utilized for pressurizing the tank. The adapter is provided with a safety valve to prevent excessive pressure being developed within the tank by the outside source. An opening, not shown, is provided at the top of the tank to enable the 30 operator to refill the tank when required.

A hand pump 21 is shown mounted on the tank which is used when no outside source of air-pressure is available. In such a situation, the operator before using the gun 10, gives the 35 piston 22 of the pump a few strokes until the desired pressure within the tank is attained. The developed pressure is indicated by the gauge 18. Where an outside source of air-pressure is available, the pump 21 may be eliminated.

Connected to the top of the tank 17 and extending therefrom to the gun 10 is a flexible hose 23, which is designated as the fluid line. Leading from the steam outlet, which is disposed within column 13, is a flexible hose 19, designated as 40 the steam line.

The gun 10, shown in Figs. 1-4, comprises a 45 hollow, heat-insulated handle 24, and a pair of tube-like members 25 and 26 extending therethrough. Member 25 has one end 27 thereof 50 grooved and connected to the fluid line 23. The

grooves 29 enable line 23 to more firmly embrace the end 27. Affixed to the other end of member 25, which projects beyond handle 24, is a hand-operated spray control nozzle 28. The nozzle is of a conventional construction and well known by those skilled in the art. Upon depressing the finger lever 30 of the nozzle, which is conveniently positioned adjacent handle 24, the fluid from tank 17 is discharged from the lower end 31 of the nozzle in the form of a spray or mist. The end 31 of the nozzle may be adjusted so as to emit either a fine or heavy spray. Various parts of the nozzle 28 may be readily disassembled for cleaning when desired.

Tube-like member 26 is positioned substantially parallel to member 25 within handle 24. One end 32 of member 26 is grooved, similar to end 27 of member 25, and is embraced by line 19. The other end 33 of member 26 projects beyond the end of the handle and is offset upwardly to form a loop. The discharge orifice 34 of end 33 is flattened somewhat so that the steam will be discharged in the form of a spray. By having end 33 looped, any condensate which might be collected in member 26 will not drip from the orifice 34 when the gun is resting on the top 12 of the table 11, as shown in Fig. 1.

As shown in Figs. 3 and 4, the end 33 of member 26 and the nozzle 28 are relatively so arranged so that the steam and fluid will be discharged to substantially the same point on the garment being cleaned when the gun is held in a relatively fixed position above the garment. Thus the operator does not have to continually move the gun so that the steam and fluid sprays will overlap.

Mounted beneath end 33 of member 26 and adjacent handle 24, is a brush 35 which may be used for loosening the dirt particles from the spotted fabric. The brush 35, in this instance, is secured to end 33 by a bracket 36. If desired, however, the bracket 36 may be eliminated and the brush mounted directly onto the underside of handle 24. It is to be understood that the term brush is meant to include any other device which may be used in rubbing the fabric.

A modified form of gun 37 is shown in Fig. 5 which is similar to the construction of gun 10, except that a third tube-like member 38 is provided. To the discharge end of member 38 is affixed a hand-controlled spray nozzle 40 which is of the same type construction as nozzle 28. In gun 37, the steam tube-like member 26 is positioned between and slightly below tube-like members 25 and 38.

When gun 37 is used an auxiliary tank 41, shown in dotted lines in Fig. 1, and containing a different type blending fluid is required. Tanks 41 and 17 are of like construction. By having two types of blending fluids available, a greater variety of fabrics may be cleaned with the gun 37. Leading from the top of tank 41 is a flexible hose 42, which is connected to tube-like member 38. Nozzles 28 and 40 and discharging orifice 34 of member 26 of gun 37 are relatively so arranged that the discharges therefrom will be directed to substantially the same area on the garment when the gun is held in a relatively fixed position above the garment.

The steam discharge for both guns 10 and 37 is controlled by one of the foot pedals 16. Thus a full head of steam is not present at the gun which would endanger the operator in case a rupture in line 19 occurred. A pressure-responsive safety device, not shown, is provided at the discharge ports of tanks 17 and 41 which will auto-

matically close off the discharge ports if a sudden drop in pressure should occur in the lines 23 and 42, respectively, due to a rupture thereof. The operator is therefore likewise protected from the pressurized fluid upon the lines 23 or 42 breaking.

In Fig. 6, still another modified form of gun 43 is shown which is similar in construction to gun 37 except that tube-like member 26 for the steam has been omitted. The brush 35 in place of being mounted on member 26 as seen in Fig. 5, is fastened directly to the underside of handle 24. The nozzles 28' and 40' are relatively so arranged as to cause the discharge therefrom to be directed to approximately the same point on the garment when the gun is held at a fixed height thereabove.

Thus it will be seen a gun has been provided which combines separate steam or fluid guns and a brush into one lightweight, convenient unit, thereby reducing the time required for performing the spot-removing operation.

While several embodiments of this invention are shown above, it will be understood, of course, that the invention is not to be limited thereto, since many modifications may be made, and it is contemplated, therefore, by the appended claims, to cover any such modifications as fall within the true spirit and scope of this invention.

I claim:

1. A garment cleaning device for use with a pressurized fluid supply, comprising an elongated hollow handle, and fluid conduit means carried within said handle and extending longitudinally therethrough; said means being connectable at one end to such a supply and having the other end thereof protruding from the end of said handle and terminating in an enlarged tip spaced from said handle end and disposed laterally to one side of the longitudinal axis of the portion of the conduit means positioned within said handle, a portion of said protruding end intermediate said handle end and said enlarged tip being disposed laterally to the opposite side of said longitudinal axis to thereby trap condensate within that portion of said fluid conduit means as positioned within said handle when the cleaning device is in its normal resting position and out of use.

2. A garment cleaning device for use with a plurality of pressurized fluid supplies, comprising an elongated hollow handle, a first fluid conduit means carried within said handle and extending longitudinally therethrough, said first conduit means being connectable at one end to one of such pressurized fluid supplies and having the other end thereof protruding from the end of said handle and terminating in an enlarged tip spaced longitudinally from said handle end and disposed laterally to one side of the longitudinal axis of the portion of said first conduit means positioned within said handle, a portion of said protruding end intermediate said handle end and said enlarged tip disposed laterally to the opposite side of said longitudinal axis to thereby trap condensate within that portion of said fluid conduit means as positioned within said handle when the cleaning device is in its normal resting position and out of use, and a second fluid conduit means carried within said handle and extending longitudinally therethrough, said second conduit means having one end thereof connectable to a second pressurized fluid supply and the other end thereof protruding from said handle and terminating at a point intermediate said handle end and the enlarged tip of said first conduit means; the protruding terminating ends of said first

and second conduit means being angularly disposed with respect to one another wherein the paths of pressurized fluid simultaneously discharged from said terminating ends will intersect one another at a point substantially equidistant from said terminating ends and offset laterally with respect to the longitudinal axis of said handle.
